DOUBLE HEAD HORN RATTLE

Le Roy Shane, Rochester, Minn.

Application September 13, 1954, Serial No. 32,262

Term of patent 7 years

(Cl. D34—15)

To all whom it may concern:

Be it known that I, Le Roy Shane, a citizen of the United States and a resident of Rochester, State of Minnesota, have invented a new, original, and ornamental Design for a Double Head Horn Rattle, of which the following is a specification, reference being had to the accompanying drawing, forming a part hereof.

Fig. 1 is a side perspective view of a double head horn rattle, showing my new design; and

Fig. 2 is a bottom plan view thereof.

I claim:

The ornamental design for a double head horn rattle, as shown.
